UNITED STATES PATENT OFFICE.

HOWARD D. CHAPMAN, OF BALTIMORE, MARYLAND, ASSIGNOR TO CARY M. STRICKLER, OF WASHINGTON, DISTRICT OF COLUMBIA.

IRON.

Application filed April 4, 1925. Serial No. 20,794.

The invention relates to improvements in an iron of the type adapted to receive a solid fuel to be consumed therein during the use of the iron to generate heat.

It is an object of the invention to provide an iron of this general type with improved means for controlling and regulating the air draft through the bed of fuel disposed within the iron during its use to insure the heating of the iron surface to a temperature sufficient to cause the iron to be successful in use.

The invention furthermore aims to provide an iron of this character in which the escaping heated gases from the top of the iron are controlled by a suitable damper and are deflected so as to be always maintained out of contact with the hands of the user.

Among other objects the invention embodies an iron by means of which the solid fuel undergoing combustion therein cannot escape during the use of the iron through the air openings; to provide an iron with an improved form of base to facilitate the combustion of the fuel; to provide an iron with a base to conduct the heat to the point of the iron where the highest temperature is desired.

In the drawings:

Figure 1 is a top plan view of the iron assembled,

Fig. 2 is a vertical longitudinal sectional view of the iron,

Fig. 3 is a transverse vertical sectional view,

Fig. 4 is a fragmentary vertical sectional view showing in detail a portion of the draft producing structure,

Fig. 5 is a horizontal sectional view clearly illustrating the bottom of the iron, and

Fig. 6 is a bottom plan view of the iron cover.

Referring now more particularly to the drawings wherein like reference characters indicate corresponding parts, the numeral 1 designates the body of the iron having the base 2 which is of the usual shape. The base and the side walls forming the body are preferably made from an integral casting of metal, the interior of the body being hollow to provide the opening 3 therein.

The iron disclosed in this application is intended to burn a solid fuel such as charcoal, coke, or any of the other well known

fuels useful for this purpose. Such fuel is placed within the fuel receiving opening 3 in the interior of the body. Means must be provided to cause a constant and proper consumption of this fuel in order that sufficient heat be generated to properly heat the base of the iron. I provide at the forward part of the iron at one side an opening 4 preferably semi-circular and leading into an air feeding and deflecting tubular member 5 for directing the air downwardly toward the base of the iron. This member has an overhanging shoulder 6 extending well within the opening in the iron for the purpose of preventing fuel from jarring out of the opening 4 during the reciprocation of the iron. A controlling valve 7 is pivoted into the iron by means of which the diameter of the air feeding opening 4 may be varied at will.

The opposite side of the iron near the rear thereof is provided with a similar opening 8. This opening leads to the tubular air passageway 9 of the same structure as heretofore described in discussing the tubular air passageway 5. The overhanging or outstanding ledge 9' is also provided to prevent the jarring of fuel through this opening when the iron is in use. The rotatable closure cap 10 is employed for controlling this opening by means of which the draft can be varied. It will be understood that the tubular air conducting passages 5 and 9 are formed by casting integrally with the sides of the wall inwardly and downwardly extending walls being, of course, spaced from the bottom of the iron body. It will be understood that by arranging the air feeding openings in this manner, that is one at the forward part of the iron at one side and the other at the rear of the iron at the opposite side there is a constant circulation of air through the iron during its reciprocation.

The base of the iron is furthermore provided with a series of grooves 11 forming spaced flanges 12 in which there are seated iron rods 13 extending towards the point of the iron. These rods are heat conductors for conducting the heat to the point of the iron which is the zone of the iron that must be most highly heated. The rods are preferably cast in the iron and form a permanent part thereof. The channels or grooves 11

in the base of the iron furthermore constitute channels of air passages through which the air can freely circulate to facilitate the combustion of the fuel in the iron.

5 A removable top or closure plate 14 is detachably secured to the iron, this plate having a forward tongue 15 that is adapted to seat within a recess or groove 16, while the rear end of the plate has a notch 17 therein 10 receiving the shiftable spring pressed detent 18 operated by the finger plunger 19. This detent 18 is carried by the U-shaped handle supporting strap 20 being supported on the spring 21 riveted to this strap so that when 15 the top is to be applied it is only necessary to move inwardly the finger member 19 and to then insert the forward tip 15 of the slot into the socket 16. By releasing the finger member 19 the detent then drops under an 20 inwardly extending catch 22 and the top is then detachably held in place. It will be seen that the top is provided with a pair of circular openings 22' disposed on each side thereof. These openings are controlled by a 25 plate 23 secured to a pin 24 extending through the top, which pin at its outer end receives a lever 25. The plate is provided with openings 26 of the same configuration as the openings 22' in the top of the iron, 30 and by rotating the handle 25 the openings in the plate and the top may be brought into or out of alignment, thereby controlling the draft in the iron. A spring 29 mounted on the supporting pin for the controlling 35 plate urges said plate upwardly so that it frictionally retains itself in any position of adjustment.

It is apparent that the issuing gases from the iron should not come in contact with the 40 hand of the user grasping the handle 30 connected with the handle carrying strap 20.

To this end a false cover 31 is provided, the same being secured to the top of the iron at its center by means of rivets 32 while the ends of the false cover are raised or spaced 45 from the cover for deflecting the gases outwardly at the side of the iron.

It will thus be seen that when the iron is in use the removable top can be taken from the base of the iron by shifting the finger 50 plug 19. Any desired solid fuel can then be placed in the iron. The dampers controlling the openings 4 and 8 in the side of the iron are regulated so that the required amount of air passes through the fuel in the 55 iron during its reciprocation. The damper in the top of the iron is also regulated by the operation of the handle 25 serving to control the discharge of exhaust gases from the iron and these gases pass out under the deflector 60 plate separated at each of its sides from the iron top. The various closures for the gas and gas openings can be set to permit any 65 regulated quantities of air or gas to pass therethrough in this way affording a very positive control for the combustion of the fuel in the iron.

Having thus described my invention, what I claim is:

In a sad iron, in combination a base and 70 a body having walls, said body being adapted to receive a solid fuel, a tubular air conducting duct leading from each side wall of the body and extending inwardly and downwardly toward the base thereof, the lower 75 wall of the duct constituting an overhanging ledge for preventing the discharge of fuel through said duct, and valves for controlling said air openings.

In testimony whereof I affix my signature.

HOWARD D. CHAPMAN.
